INFANT'S GARMENT

Philip G. Siegel, New York, and Martin Stein, Bronx, N. Y., assignors to Perfect Knit Togs, Inc., New York, N. Y., a corporation of New York

Application October 14, 1955, Serial No. 540,403

2 Claims. (Cl. 2—80)

This invention relates to clothing and more particularly to an infant's creeper.

The clothing of infants presents unique problems as any parent knows. These problems are founded on the necessity that the garment known as a diaper be worn, coupled with the desire of the parents that the infant be neatly dressed. The latter requirement means that the diaper should be considered an undergarment over which is worn an outer garment of attractive appearance. Implicit in the use of a diaper is that fact that this garment must, not infrequently, be changed, and this fact leads to a necessity for a construction of outer garment which, while neat and attractive, permits easy and convenient access to the diaper.

In a prior patent, No. 2,576,812 issued November 27, 1951, to Philip G. Siegel, one of the inventors herein, is disclosed a one piece infant's garment which has met the enumerated requirements. However, tastes in fashion in the case of infant's wear, as in other fields of apparel, fluctuate. More recently, the two piece outfit for infants has come into vogue, consisting of a panty and an overblouse. Our present invention, while utilizing some features described in the prior Patent No. 2,576,812 referred to above, is for an entirely new garment which meets the dictates of the current vogue, yet in every respect preserves and improves upon the virtues of that earlier garment.

It is the primary object of this invention to provide a garment having separable panty and overblouse portions, in which the panty portion is prevented from slipping down, and the overblouse portion is prevented from creeping up. The garment may be worn by any infant, and will properly function, even though the configuration of his body may be different than that which may be considered average. The concept of an average configuration of body becomes necessary because it is anticipated that the garment disclosed here will be mass produced in a plurality of standard sizes, and for this reason it is not possible to accommodate every variation in body proportions as is possible with custom fitting. Every garment can be constructed through use of our invention so that variations in length of torso, in abdominal dimension and size of thigh are immaterial to good fit for a given size of garment. This, of course, is basic in the mass production of garments. In order to achieve this universality of size, a means of releasable attachment utilizing unique flaps between the two portions of the garment is provided. By this means the two portions of the garment can be attached together to hold the panty in place and present a neat appearance, even though the top of the panty may meet the interior of the overblouse at different positions with different wearers of the garment. Moreover, our garment is characterized by the feature that it is not necessary to tighten the diaper in order to hold it up, for this causes discomfort to the child. Instead, the panty, which encloses the diaper, being attached to the overblouse, will serve to hold the diaper up. Because of the various aspects of our novel garment alluded to above, it

2

is apparent that use of the garment will always afford a dressed up look with top and panty portions in alignment, and without the possibility of a fallen diaper or an uncovered midriff. This condition will obtain even when the child crawls or otherwise moves about.

Another object herein is to provide, in a separable infant's creeper, for ready and easy access to the underlying diaper with no detract from the attractive appearance of the garment, and in which garment it is extremely easy to dress the infant in the first place. The panty portion is so constructed that it may be opened in a first manner to quickly reveal the diaper for changing. During this operation, the components of the panty portion, which may be made with a moisture proof lining, may be so disposed as to prevent any unfortunate soiling of the bed clothes or other surface, the components themselves receiving the soiling. The garment is also notable in that, should there be any such soiling, the component of the panty soiled may be independently laundered, without requiring laundering of the whole garment. This being the case, it is apparent that components of the garment may be replaced by other interchangeable components so that the garment is not rendered useless in toto when it is soiled only locally. Alternatively, the panty portion may be opened in a second manner so that it may, even while assembled to the overblouse, be spread out for very easy dressing of the child, saving wear and tear on both parent and child.

Still another object is to provide a system of construction in an infant's garment in which portions of the garment may be replaced without the necessity for scrapping the whole garment if only part is damaged. This is obviously the case where separable top and panty portions are used as is the case with our structure. In addition, our garment may be made with completely separable front and rear portions in the panty. Such a system of construction would be especially beneficial in periods of materials shortage, in that only a part of the garment, upon wearing out, need be replaced by a new part.

How these and many other objects are to be implemented will become clear through a consideration of the accompanying drawings wherein:

Fig. 1 shows a front view of the novel garment in an assembled condition,

Fig. 2 is a view of the garment laid open for convenient dressing of an infant.

Fig. 3 is a section taken at 3—3 of Fig. 2, and

Fig. 4 is an enlarged view of the garment at the vicinity where blouse and panty are releasably joined.

The garment shown in the drawings includes an overblouse 10 having a back panel 11 and front panels 12 and 13 which join back panel 11 at the vertical side seams 14 and 15 respectively. Triangular flaps of material 16 and 17 are included respectively into each of seams 14 and 15. Flaps 16 and 17 are identical and a description of one will suffice for both. One edge or leg 20 of each of the flaps is sewn into the respective seams. A second edge or leg 21 extends at a right angle to edge or leg 20, so that leg 21 and the hypotenuse of the triangular flap are free. The female portion 22 of a snap fastener is mounted near the free end of edge 21.

Also comprising part of the garment is the panty 23 which has a front portion 24 and a rear portion 25. Each portion 24 and 25 is of two plies, the outer 26 being of any suitable fabric and the inner 27 being of a moisture proof material. The portions 24 and 25 are completely detachable from each other by means of snap fasteners 30. Thus the front portion 24, for example, may be completely removed from the garment and replaced by a clean front portion. The top of the rear portion 25 is folded over and an elastic strip 31 included within the resulting hem to give a shirred band 32 across the top of rear

portion 25. Mounted into shirred band 32 are male portions 33 of snap fasteners, which are designed to mate with female portion 22 mounted on the triangular flaps 16 and 17. The panty 23 is thus held in releasable engagement within overblouse 10.

Because of the unique garment which we have thus created, great versatility in its use is possible. Either overblouse 10 or panty 23 may be separated from the other and changed where it is not necessary to launder the entire garment. Moreover, dressing a baby is extremely easy, for it is necessary only to open the overblouse, and to open the panty from one side or other, place the baby on the substantially flat surface thus exposed, and then to redo the snaps of the panty and the buttons or other fastening means of the blouse. In addition, changing the diaper is made very easy, and protection to bed clothes as well as parent during the process is provided. All that is necessary is to open the overblouse, then undo the crotch and all side snap fasteners in the panty except the top-most on each side, which are left secured to keep front and rear portions 24 and 25 of the panty in engagement, and to flip back the front portion 24 of the panty. The diaper may thus be quickly and completely exposed for changing, the moisture proof inner plies 27 of the panty meanwhile providing protection to adjacent areas.

While we have described a specific embodiment of our invention, it is apparent that changes and modifications may be made therein, and that garments containing such changes and modifications will fall within the ambit of our invention.

We claim:

1. An infant's garment comprising an overblouse portion having a back panel and front panels joined to said back panel along vertical side seams, and a panty portion for fitting over a diaper, and means for separably attaching said overblouse and panty portions, said means comprising a pair of substantially triangular flaps, each having a substantially right angle therein, and each having a leg sewn into one of said vertical side seams, the remaining leg and hypotenuse of each of said triangular flaps being free, coupling means mounted on each of said flaps substantially at the intersection of said remaining leg and

hypotenuse thereof, and coupling means mounted on said panty portion substantially at the top thereof for releasable engagement with the said coupling means mounted on said flaps.

5. 2. An infant's garment comprising an overblouse portion having a back panel and front panels joined to said back panel along vertical side seams, and a panty portion open at the top for fitting over a diaper, said panty portion being comprised of front and rear panels, and having 10 leg openings, and a crotch side between said leg openings, and releasable mutually interengaging coupling means mounted on said front and rear panels along the vertical sides and crotch side thereof, whereby said front and rear panels may be partially separated, leaving said panels joined alternatively along a horizontal axis or a vertical axis, and means for separably attaching said overblouse and panty portions, said means comprising a pair of substantially triangular flaps, each having a substantially right angle therein, and each having a leg sewn into one of said vertical side seams, the remaining leg and hypotenuse of each of said triangular flaps being free, coupling means mounted on each of said flaps substantially at the intersection of said remaining leg and hypotenuse thereof, and coupling means mounted on said panty portion substantially at the top thereof for releasable engagement with the said coupling means mounted on said flaps.
